UNITED STATES PATENT OFFICE.

VERNON ROYLE, OF PATERSON, NEW JERSEY.

STRAINER HEAD FOR TUBING MACHINES.

Application filed January 25, 1922. Serial No. 531,797.

This invention relates to a strainer head for tubing machines, with an object in view of providing a device of this character that will adapt the machine for satisfactory and expeditious operation upon materials of varying characteristics without producing an undue strain upon any of the parts or irregularity in operation.

Another object is to provide such a device which may be applied to standard forms of tubing machines without the necessity of partial reconstruction or alteration.

Another object is to provide a device of this character which may be very quickly and simply opened for cleaning and access to the inner parts and as quickly and easily returned to operative position.

Another object consists in providing a device of this character in which the separable parts of the strainer head are so braced and interlocked as to guard against distortion or breakage.

Another object consists in providing certain improvements in the form, construction and arrangement of the several parts whereby the above named and other objects may be effectively attained.

Machines of this character are designed to operate upon rubber compounds, including various substances, during the process of reclaiming the rubber, and these materials vary greatly in consistency. Consequently, it has been found that strainer heads heretofore in use have not been fully adequate to handling these different materials with satisfactory results in all respects. My invention is designed to overcome this disadvantage.

A practical embodiment of my invention is represented in the accompanying drawings in which

Fig. 1 represents a top plan view of the strainer head secured to the cylinder of a tubing machine, the latter being broken away.

Fig. 2 represents a face view of the same.

Fig. 3 represents a horizontal central section through the part shown in Fig. 1, certain elements being shown in different positions in full and dotted lines.

Fig. 4 represents a section taken in the plane of lines IV—IV of Fig. 1, looking in the direction of the arrows.

Fig. 5 represents a large detailed section

showing the means for locking the two parts of the strainer head.

Fig. 6 represents an enlarged detailed section, showing the locking bar and adjacent parts.

The strainer head is adapted for use in connection with a tubing machine of standard or appropriate form and is, as will be understood by operatives in this industry, intended to be secured to the cylinder of the tubing machine in which the screw or plodder operates.

In the present instance, the cylinder is denoted by 1 and the liner for its bore by 2. The screw or plodder which operates in the said bore in the usual manner is indicated by 3.

The strainer head includes a face plate 4, which constitutes a supporting member and is of such size as to conform substantially to the end of the cylinder 1. The said plate has four holes fitted to receive stud bolts 5 that project from the cylinder and receive nuts 6 for securing the plate to the cylinder. The plate 4 is of open construction and its inner diameter corresponds with the outer diameter of the liner 2. A suitable washer 7 may be interposed between the plate 4 and the cylinder 1.

The strainer head also includes a tubular element that has an inner member 8, which is threaded into the bore liner 2, as clearly shown at 9, and engages with a sliding fit the interior of the face plate 4. The inside of the member 8 is directly in line with and of the same diameter as the interior of the liner 2, so that the said member, in effect, constitutes a prolongation of the bore of the cylinder in which the screw 3 can operate. The forward end of the member 8 is open and its side walls are pierced by a multiplicity of circular holes 10.

The said tubular element also comprises an outer member or jacket which is composed of two semicircular halves 11, 12, which are substantially identical. These halves of the outer member are provided with hinged knuckles 13, 14 that are fitted to receive pintles 15, 16 which are journaled in lugs 17, 18, that project from the front of the plate 4. This arrangement enables the halves 11, 12 to swing toward and away from each other and hence toward and away from the member 8. When the said halves are swung toward each other to the limit

of their movement, they together constitute a member of cylindrical form, which is concentric with and surrounds the inner member 8, leaving a space between said two members.

The forward ends of the halves 11, 12, are provided with threaded flanges 19, 20 which, when united, are designed to receive a nut 21, which locks them together. Suitable 10 spacing plugs 22 are carried by the half 12 in position to be engaged by the edge of the half 11, in order to assist in proper alignment of the two halves and matching of the threads on the flanges 19, 20, so that the nut 21 will accurately fit. The plugs 22 may be threaded into the half 12, for the purpose of adjustment, or they may be plain and the adjustment effected by filing.

The plate 4 has a circular rib 23 formed 20 thereon surrounding the inner member 8, which rib constitutes a shoulder against which the inner ends of the halves 11, 12 rest when closed together; thereby insuring rigidity and also assisting in perfect alignment of the parts. The halves 11, 12 are also provided with a multiplicity of circular holes 24, 25, and it will be noted that the diameter of these holes is considerably less than the diameter of the holes 10 in the 30 inner member 8, and that the holes in the said outer and inner members are not coincident, that is, are not in line.

The end member 26 is fitted to seat within the front portion of the outer member composed of the halves 11, 12, and to be secured 35 therein by the nut 21, which clamps the said end member between itself and the inner member 8. This end member also has a multiplicity of circular holes 27 passing therethrough. It will be observed from the foregoing description that the holes in the inner and outer tubular members lie at right angles to the axis of the screw 3, while the holes in the end member are parallel to the 45 said axis.

A screen 28 surrounds the inner member 8 and is seated in a circular recess 29 formed in that portion of the inner member 8 which fits within the plate 4, as clearly shown in 50 Fig. 3. The location of this screen is such that it will intervene between the inner member 8 and the outer member constituted by the halves 11, 12, and lie adjacent the interior of the latter when they are in closed 55 position. A flat screen 30 is placed between the end member 26 and the inner member 8 and clamped in position through the action of the nut 21. The rear ends of the halves 11, 12 are bevelled off as shown at 31, 32, 60 so as to clear the member 8 when the halves are swung inwardly and outwardly.

Suitable pipes 33, 34 may be arranged and connected with a channel 35 in the face plate 4 in order to supply a cooling or heating 65 medium to the head. By arranging the

channel 35 in the plate 4, I am able to heat the material immediately prior to its ejection from the cylinder into the strainer head and thus cause it to be more readily worked in and through the strainer head.

As the operation of the screw 3 upon the material is very powerful and the force exerted in a lateral direction through the passage of the material through the sides of the strainer head is very great, it will be apparent that there is a severe strain upon the halves 11, 12 of the outer member and a tendency to cause them to bulge and separate intermediate to their ends. In order to meet this tendency and prevent any injury from occurring I provide a pair of lock bars 36, 37 which are provided with hinged knuckles 38, 39 that engage pintles 40, 41 which are mounted in lugs 42, 43 that are formed integrally with the face plate 4. As a result of this arrangement the said lock bars can swing vertically or in a plane at right angles to the plane of swinging movement of the halves 11, 12, so as to be brought into or out of cooperative or locking engagement with the said halves when the latter are in closed or operative position. The lock bars 36, 37 have their inner faces provided with longitudinal grooves or channels 44, 45 which leave a pair of ribs 46, 47 at each side of the said channels. The adjacent parts of the halves 11, 12 are provided with two pairs of grooves 48, 49 fitted to receive the said ribs 46, 47; and it will be seen that the fashioning of these grooves 48, 49 produces corresponding pairs of ribs 50, 51 which are adapted to enter the channels 44, 45 in the lock bars 36, 37. This construction enables each of the said lock bars to interlock with the halves 11, 12 throughout the length of the latter so as to firmly hold them in operative alignment and prevent any distortion of the same during the operation of the machine. It will be noted that the grooves 48, 49 are larger in cross section than the ribs 46, 47 so that there may be a ready interengagement of the parts, the outer sides of the said grooves and ribs being slightly rounded so as to facilitate this. However, the operative engaging faces of the said ribs and grooves are straight and parallel so as to cause the locking to be rigid with the parts in perfect alignment. This construction is well shown in Fig. 6.

For the purpose of firmly clamping and securing the lock bars in engagement with the halves of the outer member of the strainer head, the nut 21 has a circular groove 52 which is bevelled on its outer edge, and this bevel is designed to cooperate with corresponding bevels formed on the exterior of the extremities of the lock bars 36, 37. The arrangement is such that, as the nut 21 is screwed on the united halves 11, 12, the groove 52 passes over the extremities of the 130

ends of the said lock bars and thereby causes them to be firmly held in operative position as clearly shown in Fig. 5. Thus the action of the nut 21 is to hold the end member 26, 5 halves 11, 12 and lock bars 36, 37 all in operative position; while the said halves prevent any lateral movement of the end member, and the said lock bars prevent any lateral distortion of the said halves.

10 The apparatus may be employed in the usual way, with the halves 11, 12 of the outer tubular member held in closed position, as shown in Figs. 1, 2 and 4. As already described, there is a space between the inner 15 tubular member 8 and the outer member composed of the halves 11, 12, while the screen 28 is spaced from the said inner member and in contact with the interior of the said outer member. As a result of this construction, the material being operated upon 20 is broken up by the holes 10 in the inner member and permitted to surge or eddy around somewhat between the said members before passing through the screen 28. This 25 protects the screen and renders it more durable and effective, as well as avoiding the clogging thereof for a longer period of time. The operation is also facilitated by making the holes 10 in the inner member greater in 30 cross section than the holes 24, 25 in the outer member, since this enables the material which has not yet been strained, to pass more freely through the inner member, while the passage of the material through the 35 screen 28 is slightly retarded by the smaller holes 24, 25, thereby protecting the screen from violent action. The fact that the holes in the inner and outer members are not in line, requires the material to follow an in- 40 direct course, which increases the effectiveness of the apparatus under certain circumstances; and by perforating the entire side and end walls of the strainer head, the outlet for material is greatly increased, thus in- 45 creasing the capacity of the machine. Finally, the provision of the lock bars for the halves of the outer member, and for coop- 50 eration with the lock nut 21, supplies abundant protection for the halves of the outer member against bulging or injury throughout their length, which bulging might result from the forceful movement of the material being operated upon if the said parts were not thus reinforced.

55 By providing the inner member 8 with a portion which bears against the inner circumference of the plate 4 and also bears against the end of the bore liner 2 as well as being threaded into the latter, the assembly 60 of the said inner member with the machine is made very firm and rigid, so that the said member will maintain perfect alignment and will be enabled to resist the great strain imparted to it.

Should the strainer head become clogged, 65 as frequently happens, or should it, for any reason, be desirable to clean any part thereof, it is a very simple matter to remove the nut 21 and swing the lock bars 36, 37 and halves 11, 12 apart, thus exposing the interior of 70 the said halves and the exterior of the screen 28 for cleaning. With the nut 21 removed, the end member 26 may also be readily taken out and the screens 28 and 30 detached for cleansing or repair. The parts may be replaced and returned to operative position in a manner obvious from the foregoing description.

It will be understood that various changes may be resorted to in the form, construction 80 and arrangement of the several parts without departing from the spirit and scope of my invention; and hence I do not intend to be limited to the details herein shown and described, except as they may be included in 85 the claims.

What I claim is:

1. A device of the character described comprising, a tubular element including a member divided to form a plurality of parts, 90 said parts being fitted to be moved into and out of operative position, and means disposed longitudinally of said parts for locking their edges in operative position.

2. A device of the character described 95 comprising, a tubular element including a member divided to form a plurality of parts, said parts being fitted to be moved into and out of operative position, and means disposed longitudinally of said parts and located at opposite sides thereof for locking their edges in operative position.

3. A device of the character described comprising, a tubular element including a member divided to form a plurality of parts, 105 said parts being fitted to be moved into and out of operative position, and means disposed longitudinally of said parts for locking their edges in operative position, said means being adapted to be swung into and 110 out of operative position.

4. A device of the character described comprising, a tubular element including a member divided to form a plurality of parts, 115 said parts being fitted to be moved into and out of operative position, means disposed longitudinally of said parts for locking their edges in operative position, and means for holding said locking means in locking position.

5. A device of the character described comprising, a tubular element including a member divided to form a plurality of parts, said parts being fitted to be moved into and out of operative position, means disposed longitudinally of said parts for locking their edges in operative position, and a cap fitted to engage the ends of said parts to hold them

in operative position and to also engage said locking means for holding it in operative position.

6. A device of the character described comprising, a tubular element including a member divided to form a plurality of parts, said parts being fitted to be moved into and out of operative position, and a lock bar disposed longitudinally of said parts and adapted to interengage with the same for holding their edges in operative position.

7. A device of the character described comprising, a tubular element including a member divided to form a plurality of parts, said parts being fitted to be moved into and out of operative position, and a plurality of lock bars disposed longitudinally of said parts and adapted to interengage with the same for holding their edges in operative position.

8. A device of the character described comprising, a tubular element including a member divided to form a plurality of parts, said parts being fitted to be moved into and out of operative position, a lock bar disposed longitudinally of said parts and adapted to interengage with the same for holding their edges in operative position, and a cap fitted to engage the ends of said parts to hold them in operative position and to also engage said lock bar for holding it in locking position.

9. A device of the character described comprising, a tubular element including a member divided to form a plurality of parts, said parts being fitted to be moved into and out of operative position, a plurality of lock bars disposed longitudinally of said parts and adapted to interengage with the same for holding their edges in operative position, and a cap fitted to engage the ends of said parts to hold them in operative position and to also engage said lock bars for holding them in locking position.

10. A device of the character described comprising, a tubular element including a member divided to form a plurality of parts, said parts being fitted to be moved into and out of operative position, and a lock bar pivoted near one end of said parts and adapted to swing longitudinally with respect thereto for interengagement therewith for holding their edges in operative position.

11. A device of the character described comprising, a tubular element including a member divided to form a plurality of parts, said parts being fitted to be moved into and out of operative position, and a plurality of lock bars pivoted near one end of said parts and adapted to swing longitudinally with respect thereto for interengagement therewith for holding their edges in operative position.

12. A device of the character described comprising, a tubular element including a member divided to form a plurality of parts,

said parts being fitted to be moved into and out of operative position, a lock bar pivoted near one end of said parts and adapted to swing longitudinally with respect thereto for interengagement therewith for holding their edges in operative position, and a cap fitted to engage the ends of said parts for holding them in operative position and to also engage said lock bar for holding it in locking position.

13. A device of the character described comprising, a tubular element including a member divided to form a plurality of parts, said parts being fitted to be moved into and out of operative position, a lock bar pivoted near one end of said parts and adapted to swing longitudinally with respect thereto for interengagement therewith for holding their edges in operative position, and a cap fitted to engage the ends of said parts for holding them in operative position, the said cap having a groove adapted to receive the end of said lock bar for holding it in locking position.

14. A device of the character described comprising, a tubular element including a member divided to form a plurality of parts, said parts being fitted to be moved into and out of operative position, a lock bar pivoted near one end of said parts and adapted to swing longitudinally with respect thereto for interengagement therewith for holding their edges in operative position, and a cap fitted to engage the ends of said parts for holding them in operative position, said lock bar having a tapered end and said cap being provided with a bevelled groove fitted to receive said tapered end for holding the lock bar in locking position.

15. A device of the character described comprising, a tubular element including a member divided to form a plurality of parts, said parts being fitted to be moved into and out of operative position, and a lock bar disposed longitudinally of said parts, said lock bar having a longitudinal channel, and said parts having projecting ribs adapted to enter said channel, whereby the lock bar may lock said parts in operative position.

16. A device of the character described comprising, a tubular element including a member divided to form a plurality of parts, said parts being fitted to be moved into and out of operative position, a lock bar disposed longitudinally of said parts, said lock bar having a longitudinal channel, said parts having projecting ribs adapted to enter said channel, whereby the lock bar may lock said parts in operative position, and a cap fitted to engage the ends of said parts to hold them in operative position and to also engage said lock bar to hold it in locking position.

17. A device of the character described comprising, a tubular element including a

- member divided to form a plurality of parts, said parts being fitted to be moved into and out of operative position, a lock bar disposed longitudinally of said parts, said lock bar having a longitudinal channel and ribs, and said parts having longitudinal grooves and ribs fitted to mate with the channel and ribs on the lock bar, whereby the lock bar may lock said parts in operative position. 5
18. A device of the character described comprising, a tubular element including a member divided to form a plurality of parts, said parts being fitted to be moved into and out of operative position, a lock bar disposed longitudinally of said parts, said lock bar having a longitudinal channel and ribs, said parts having longitudinal grooves and ribs fitted to mate with the channel and ribs on the lock bar, whereby the lock bar may lock 15 said parts in operative position, and a cap fitted to engage the ends of said parts to hold them in operative position and to also engage said lock bar to hold it in locking position. 20
19. A device of the character described comprising, a tubular element including a member divided to form a plurality of parts, said parts being fitted to be moved into and out of operative position, and a lock bar pivoted near one end of said parts, said lock bar having a longitudinal channel, said parts having projecting ribs adapted to enter said channel, whereby the lock bar may lock the said parts in operative position. 25
20. A device of the character described comprising, a tubular element including a member divided to form a plurality of parts, said parts being fitted to be moved into and out of operative position, a lock bar pivoted near one end of said parts, said lock bar having a longitudinal channel, said parts having projecting ribs adapted to enter said channel, whereby the lock bar may lock the said parts in operative position, and a cap fitted to engage the ends of said parts to hold them in operative position, said cap being provided with a groove adapted to engage the end of said lock bar for holding it in locking position. 35
21. A device of the character described comprising, a tubular element including a member divided to form a plurality of parts, said parts being fitted to be moved into and out of operative position, and a lock bar pivoted near one end of said parts, said lock bar having a longitudinal channel and ribs, said parts having longitudinal grooves and ribs fitted to mate with the channel and ribs on the lock bar, whereby the lock bar may lock said parts in operative position. 45
22. A device of the character described comprising, a tubular element including a member divided to form a plurality of parts, said parts being fitted to be moved into and out of operative position, a lock bar pivoted near one end of said parts, said lock bar having a longitudinal channel and ribs, said parts having longitudinal grooves and ribs fitted to mate with the channel and ribs on the lock bar, whereby the lock bar may lock said parts in operative position. 55
23. A device of the character described comprising, a tubular element including a member divided to form a plurality of parts, said parts being fitted to be moved into and out of operative position, a lock bar pivoted near one end of said parts and having its free end tapered, said lock bar having a longitudinal channel, and said parts having projecting ribs adapted to enter said channel, whereby the lock bar may lock the said parts in operative position, and a cap fitted to engage the ends of said parts for holding them in operative position, said cap being provided with a bevelled groove adapted to engage the tapered end of said lock bar for holding it in locking position. 60
24. In combination with the cylinder of a tubing machine having a bore liner, a strainer head including a perforate element fitted to be threaded into said bore liner and have a sliding fit within the said cylinder. 65
25. In combination with the cylinder of a tubing machine having a bore liner, a strainer head including a perforate element fitted to be threaded into said bore liner and have a sliding fit within said cylinder while abutting the end of said liner. 70
26. In combination with the cylinder of a tubing machine, a strainer head, a plate for securing the strainer head to said cylinder, said strainer head having a perforate element fitted to be threaded into said cylinder and have a sliding fit with the interior of said plate. 75
27. In combination with the cylinder of a tubing machine, having a bore liner, a strainer head, a plate for securing the strainer head to said cylinder, a perforate element fitted to be threaded into said liner and have a sliding fit with the interior of said cylinder and plate. 80
28. In combination with the cylinder of a tubing machine, having a bore liner, a strainer head, a plate for securing the strainer head to said cylinder, a perforate element fitted to be threaded into the said liner and have a sliding fit with the interior of said cylinder and plate, while abutting the end of said liner. 85
- In testimony, that I claim the foregoing as my invention, I have signed my name this 18th day of January, 1922. 90

VERNON ROYLE.
